H. L. & C. L. Reynolds
ATTORNEYS

UNITED STATES PATENT OFFICE.

WILLIAM F. WOLLESEN, OF RAYMOND, WASHINGTON.

SASH FASTENER.

1,412,154.

Specification of Letters Patent. Patented Apr. 11, 1922.

Application filed October 25, 1920. Serial No. 419,241.

To all whom it may concern:

Be it known that I, WILLIAM F. WOLLESEN, a citizen of the United States of America, and resident of the city of Raymond, in the county of Pacific and State of Washington, have invented certain new and useful Improvements in Sash Fasteners, of which the following is a specification.

My invention relates to sash fasteners and is particularly adapted for securing the two sashes of a window in fixed relative position when either sash is partially opened.

An object of my invention is to provide means which will hold two sashes relatively fixed and which may be quickly placed in operative position or held in inoperative position.

It is particularly an object of my invention to provide means for holding a sash lock in inoperative position against its normal tendency to remain in operative position, these means being quickly and easily operated.

My invention comprises those novel parts and combinations thereof which are shown in the accompanying drawings, described in the specification and particularly defined by the claims terminating the same.

In the accompanying drawings I have shown my invention in the form which is now preferred by me.

Figure 1 is an elevation of two sashes equipped with my sash fastener, parts being shown in operative or locking position.

Figure 2 is a section through the two sashes showing my sash fastener in elevation in operative position.

Figure 3 is a view similar to Figure 2 showing parts in inoperative position.

I prefer to mount my device in a suitable standard which may be secured upon the top rail of the lower sash A. The standard 1 is formed with a pair of upstanding pivot ears. Pivotedly mounted within the standard, at 10, is a securing cam 2. This is eccentrically pivoted in the standard 1 and engages the upper sash B by one edge. This edge may have a corrugated facing, as shown at 20 which may be of rubber or other suitable material, and which engages and grips the sash B.

A spring, as shown at 3, may be coiled about the pivot pin 10, and engages both the standard 1 and the cam 2, to hold the corrugated surface 20 normally against the sash B. In this position a force, acting to

raise the sash A, is resisted by the grip of the surface 20 upon the sash B. Similarly, any attempt to lower the sash B is resisted in the same manner through the sash A. 60

It is at times desirable to hold the cam 2 in inoperative position. The means which I have shown for accomplishing this consist of a socket 21, which is formed in a side face of the cam 2, and a pin 4 which is mounted in the standard 1 to slide towards and from the cam 2, and which has an end 40 engageable therein. I prefer that this pin be normally held out of engagement with the socket 21 and hence provide a 70 spring 41 positioned between the head 42 of the pin and the sleeve 11 formed in the standard 1, in which the pin slides. The end 40 is enlarged and prevents withdrawal of the pin in this direction. 75

Whenever it is desired to hold my device in inoperative position it is thrown back into the position shown in Figure 3 and the pin 4 is pushed toward the cam 2 against the resistance of the spring 41, until the end 80 40 engages within the socket 21.

It is held in this position by the frictional engagement of the end 40 within the socket 21, caused by the tendency of the spring 3 to return the cam to its normal operative position. Whenever it is desired to release the pin 4, this may be done by withdrawing its end 40 from the socket 21, when the spring 41 will further retract the pin and will hold it in inoperative position. It can be 85 seen that both the locking and unlocking of the cam by the pin 4 may be quickly and easily accomplished by the use of my construction as described. Furthermore, the pin may not be withdrawn from the standard 1 and hence is never misplaced when it is desired for use. 90 95

What I claim as my invention is:

1. In a sash fastener, in combination, a standard adapted to be secured upon the top 100 of the lower sash, a cam pivotally mounted in said standard and adapted to engage the upper sash, means secured within said standard for securing said cam in inoperative position, and means automatically operative to hold said cam-securing means normally in inoperative position, said cam and the cam-securing means being frictionally engageable. 105

2. In a sash fastener, in combination, a 110 standard adapted to be secured upon the top of the lower sash, a cam pivotally

mounted in said standard and adapted to engage the upper sash, means normally holding said cam in sash-engaging position, means secured within said standard for 5 securing said cam in inoperative position, and means automatically operative to hold said cam-securing means normally in inoperative position, said cam and the cam-securing means being frictionally engage- 10 able.

3. In a sash fastener, in combination, a standard adapted to be secured upon the top of the lower sash, a cam pivotally mounted in said standard and adapted to engage the 15 upper sash, said cam having a socket in a side face, a pin slidably mounted in said standard for movement towards and from said cam, and engageable within said socket, and a spring engaging said pin and operable 20 to hold the same normally in inoperative

position, the pin being engageable frictionally in said socket in opposition to said spring.

4. In a sash fastener, in combination, a standard adapted to be secured upon the 25 top of the lower sash, a cam pivotally mounted in said standard and adapted to engage the upper sash, said cam having a socket in a side face, a pin slidably mounted in said standard for movement towards and 30 from said cam, and engageable within said socket, a spring engaging said pin and operable to hold the same normally in inoperative position, the pin being engageable frictionally in said socket in opposition to 35 said spring, and heads on both ends of said pin to prevent removal thereof.

Signed at Raymond, Pacific County, Washington, this 16th day of October, 1920.

WILLIAM F. WOLLESEN.
